(57) **CLAIM**

The ornamental design for a hair dryer, as shown and described.

DESCRIPTION

FIG. 1 is a front, right and top perspective view of a hair dryer, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of a portion of the hair dryer shown within the area designated as 9 in FIG. 1;

FIG. 10 is an enlarged view of a portion of the hair dryer shown within the area designated as 10 in FIG. 2; and,

FIG. 11 is an enlarged view of a portion of the hair dryer shown within the area designated as 11 in FIG. 2.

The broken lines shown in the drawings illustrate portions of the hair dryer that form no part of the claimed design.

The dot-dash broken lines encircling portions of the hair dryer in FIGS. 1 and 2 and illustrated in the enlarged views in FIGS. 9, 10 and 11 form no part of the claimed design.

1 Claim, 11 Drawing Sheets
